CLAIM

The ornamental design for a display screen with a stand, as shown and described.

DESCRIPTION

1. Display screen with a stand
1.1 is a front, top and right side perspective view of a display screen with a stand showing our new design;
1.2 is a front elevation view thereof;
1.3 is a back elevation view thereof;
1.4 is a left side elevation view thereof;
1.5 is a right side elevation view thereof;
1.6 is a top plan view thereof;
1.7 is a bottom plan view thereof; and
1.8 is another front, top and right side perspective view thereof, shown in an environment of use.

(Continued)

The broken lines indicate portions of the article that form no part of the claimed design.

1 Claim, 8 Drawing Sheets
